Primary Examiner — Selina Sikder(74) *Attorney, Agent, or Firm* — Young & Thompson**CLAIM**

The ornamental design for a milking point control unit, as shown and described.

DESCRIPTION

FIG. 1 is a front, left side, and top perspective view of a milking point control unit showing the new design;

FIG. 2 is a left side elevation view thereof;

FIG. 3 is a front elevation view thereof;

FIG. 4 is a right side elevation view thereof;

FIG. 5 is a top plan view thereof;

FIG. 6 is a rear elevation view thereof; and,

FIG. 7 is a bottom plan view thereof.

The broken lines shown in the drawings illustrate portions of the milking point control unit that form no part of the claimed design.
